US00D692941S

(12) **United States Design Patent**
Klinar et al.

(10) **Patent No.:** **US D692,941 S**
(45) **Date of Patent:** **** Nov. 5, 2013**

(54) **3D GLASSES**

(75) Inventors: **Miha Klinar**, Radovljica (SI); **Martin Sostaric**, Ljubljana (SI); **Andraz Sapec**, Ljubljana (SI); **Maria Costeira**, Paphos (CY); **Tjasa Vrhovnik**, Borovnica (SI); **Jure Bezgovsek**, Velenje (SI); **Domen Gazzvoda**, Ljubljana (SI); **Luka Stepan**, Kranj (SI)

(73) Assignee: **X6D Limited**, Limassol (CY)

(**) Term: **14 Years**

(21) Appl. No.: **29/373,887**

(22) Filed: **Jun. 3, 2011**

Related U.S. Application Data

(63) Continuation-in-part of application No. 29/392,398, filed on May 20, 2011, now Pat. No. Des. 669,522, and a continuation-in-part of application No. 29/381,373, filed on Dec. 10, 2010, now abandoned, and a continuation-in-part of application No. 29/378,689, filed on Nov. 8, 2010, now abandoned, and a continuation-in-part of application No. 29/369,654, filed on Sep. 10, 2010, now Pat. No. Des. 671,590, and a continuation-in-part of application No. 29/368,714, filed on Aug. 27, 2010, now abandoned, said application No. 29/373,887 is a continuation-in-part of application No. 13/019,896, filed on Feb. 2, 2011, and a continuation-in-part of application No. 12/619,518, filed on Nov. 16, 2009, now abandoned, and a continuation-in-part of application No. 12/619,517, filed on Nov. 16, 2009, now abandoned, and a continuation-in-part of application No. 12/619,456, filed on Nov. 16, 2009, now abandoned, and a continuation-in-part of application No. 12/619,431, filed on Nov. 16, 2009, now abandoned, and a continuation-in-part of application No. 12/619,415, filed on Nov. 16, 2009, now abandoned, and a continuation-in-part of application No. 12/619,400, filed on Nov. 16, 2009, now abandoned, and a continuation-in-part of application No. 12/619,309,

filed on Nov. 16, 2009, now abandoned, and a continuation-in-part of application No. 12/619,163, filed on Nov. 16, 2009, now abandoned, and a continuation-in-part of application No. 12/619,102, filed on Nov. 16, 2009, now abandoned, said application No. 29/373,887 is a continuation-in-part of application No. 13/113,784, filed on May 23, 2011, said application No. 29/373,887 is a continuation-in-part of application No. 29/393,095, filed on May 31, 2011, which is a continuation of application No. 29/381,373, which is a continuation of application No. 29/378,689.

- (57) **CLAIM**
 We claim the ornamental design for 3D glasses, as shown and described.
- DESCRIPTION**
- The file of this patent contains at least one drawing executed in color. Copies of this patent with color drawing(s) will be provided by the Office upon request and payment of the necessary fee.
- FIG. 1 is a top perspective view of one embodiment of the 3D glasses of our invention;
 FIG. 2 is a front elevation view of the 3D glasses of FIG. 1;
 FIG. 3 is rear elevation view of the 3D glasses of FIG. 1;
 FIG. 4 is a top plan elevation view of the 3D glasses of FIG. 1;
 FIG. 5 is a right side elevation view of the 3D glasses of FIG. 1;
 FIG. 6 is a bottom plan elevation view of the 3D glasses of FIG. 1;
 FIG. 7 is a left side elevation view of the 3D glasses of FIG. 1;
 FIG. 8 is a top perspective view of another embodiment of the 3D glasses;
 FIG. 9 is a front elevation view of the 3D glasses of FIG. 8;
 FIG. 10 is rear elevation view of the 3D glasses of FIG. 8;
 FIG. 11 is a top plan elevation view of the 3D glasses of FIG. 8;
 FIG. 12 is a right side elevation view of the 3D glasses of FIG. 8;
 FIG. 13 is a bottom plan elevation view of the 3D glasses of FIG. 8;
 FIG. 14 is a left side elevation view of the 3D glasses of FIG. 8;

FIG. 15 is a top front perspective view of another embodiment of the 3D glasses;
FIG. 16 is a bottom rear perspective view of the 3D glasses of FIG. 15;
FIG. 17 is bottom front perspective view of the 3D glasses of FIG. 15;
FIG. 18 is a top rear perspective view of the 3D glasses of FIG. 15;
FIG. 19 is a left front perspective view of the 3D glasses of FIG. 15;
FIG. 20 is a front elevation view of the 3D glasses of FIG. 15;

FIG. 21 is a rear elevation view of the 3D glasses of FIG. 15;
FIG. 22 is a rear perspective view of the 3D glasses of FIG. 15, showing the ear-pieces in a folded position; and,
FIG. 23 is a front left perspective view of the 3D glasses of FIG. 15.

The hatched or shaded areas in FIGS. 1-7 are illustrative to indicate a region(s) of the glasses that is of a contrasting tone or color, no specific colors are being claimed in FIGS. 1-7.
